INVENTOR:

BY *Edward Laws*
ATTORNEYS.

UNITED STATES PATENT OFFICE.

EDWARD LAWS, OF CINCINNATI, OHIO, ASSIGNOR TO THE GUSTAVE-FOX COMPANY,
OF CINCINNATI, OHIO, A CORPORATION OF OHIO.

DEVICE FOR ATTACHING NAME-PLATES AND THE LIKE.

1,371,696.

Specification of Letters Patent.

Patented Mar. 15, 1921.

Application filed December 4, 1920. Serial No. 428,196.

To all whom it may concern:

Be it known that I, EDWARD LAWS, citizen of the United States, and resident of Cincinnati, in the county of Hamilton and State 5 of Ohio, have invented certain new and useful Improvements in Devices for Attaching Name-Plates and the like, of which the following is a full, clear, and exact description, reference being had to the drawings 10 forming part of this specification.

My invention relates to devices for attaching name plates to automobile radiator hoods and the like.

There are numerous devices adopted in 15 the art for the purpose of securing name plates in place, usually on the sheet metal construction found at the front of the radiators of automobiles. These devices rely mainly for the permanency, and ready 20 mountability of the name plates on spring action, the spring being that inherent in the metal of the name plate or some attachment thereto.

According to my invention the means employed for attachably securing the name plate in place involves the turning inwardly 25 on a boss plate at the back of the name plate of a sharp or rough metal edge, which when forced over an annular flange on the radiator 30 shell will tightly and permanently grip the said flange, until some distortion of the metal of the shell serves to permit a disengagement.

As in previous devices the object of my 35 invention is to provide a cheap and strong method of attaching a name plate on a sheet metal structure, in a single motion, and with large chances of permanency while in use.

This object I accomplish by that certain 40 construction and arrangement of parts to be hereinafter more specifically pointed out and claimed.

In the drawings,

Figure 1 is a front elevation showing the 45 device.

Fig. 2 is a section of that portion of a metal shell to which my device is to be attached, showing the formed up conformation thereof at said point.

50 Fig. 3 is a central section of the name plate with its rear boss plate.

Fig. 4 is a central section through the assembly of plate and sheet metal shell.

Fig. 5 is a detail front elevation of the 55 parts shown in Fig. 2.

Fig. 6 is a detail front elevation of the parts shown in Fig. 3.

It will be understood that while the chief mode of use of my invention will be in the securing of name plates on automobile radiator shells, that I do not limit the application thereof to this one use, and use the terms relative to such use as merely exemplary terms, inclusive of all analogous uses and structures.

I provide in connection with a name plate 1, same bearing suitable insignia, or the like, a conical boss plate 2, mounted fixedly thereon. The metal at the annular crest of this conical boss is bent inwardly at an inward 60 angle to the axis of the cone, as at 3 to form a biting edge, to be used in effecting the necessary grasp in mounting the plate.

The sheet metal piece 4, in this instance a radiator shell to which the plate is to be 70 attached, is formed up with a conical depression 5, to match the conical boss or ring, on the rear of the name plate, and the metal at the crest of the depression, is bent outwardly to form an annular flange 6, same 75 being of a size to engage in the hole in the boss.

In attaching the name plate, the hole in the boss is set over the flange at the base of the radiator shell depression and the plate 85 forced in. This will cause the edge 3 of the boss to engage over and slide down the flange, to the base of the shell depression, and this said edge, being a close fit, will 90 compress the flange to the extent necessary for it to slide home, and will thereupon grasp the same, so as to be practically irremovable without distortion of the flange or the boss.

It may be observed that this mounting 95 device does not have to rely upon spring action, but rather upon the effect of a sharp metal edge engaging in a tight fit over another metal piece. There is nothing to get out of shape in the handling of the name plate and boss, and the tendency of the 100 radiator shell to weaken or split when pressing the name plate home, will be counteracted by the rounded walls of the depression therein.

Thus my device is superior to those which 105 provide a member to force within a plain round hole formed in a radiator shell since in such a case a slight oversize on the part of the member forced into such hole would be likely to distort, weaken or split the metal 110

exposing non-enameled edges to rust action, breaking the enamel, permitting the name plate to rattle, and like defects which are obvious.

5 Having thus described my invention what I claim as new and desire to secure by Letters Patent, is:—

1. In a device for attaching a name plate or the like to a metallic shell, the combination with a shell having a hole therein, a wall extending toward the plate from said hole, of a name plate or the like, and a member on the rear of the name plate adapted to engage the metal walls about said hole 10 on the outside thereof by a tight metallic fit, said member having a metallic edge forced against the walls about said hole, for the purpose described.

15 2. In a device of the character described

the combination of a shell of metal having a 20 conical depression therein, and a flange turned outwardly from the base of the depression, of a name plate having a conical extension on the rear thereof, said extension having a hole adapted to be forced over the 25 said flange.

3. In a device of the character described the combination of a shell of metal having a 30 conical depression therein, and a flange turned outwardly from the base of the depression, of a name plate having a conical extension on the rear thereof, said extension having a hole adapted to be forced over the 35 said flange, said extension having the metal about the hole turned inwardly at an angle to the axis thereof, so as to grasp the metal walls of said flange.

EDWARD LAWS.
